UNITED STATES PATENT OFFICE.

MORTON G. BUNNELL, OF CHICAGO, ILLINOIS, ASSIGNEE TO FREDERICK C. AUSTIN, OF CHICAGO, ILLINOIS.

AUTOMATIC WINDOW-SCREEN.

1,115,499.

Specification of Letters Patent.

Patented Nov. 3, 1914.

Application filed December 9, 1910. Serial No. 596,422.

To all whom it may concern:

Be it known that I, MORTON G. BUNNELL, a citizen of the United States of America, and resident of Chicago, Cook county, Illinois, have invented a certain new and useful Improvement in Automatic Window-Screens, of which the following is a specification.

My invention relates to automatic window screens of the kind in which the screen is carried on a roller and automatically unwound therefrom when the window is opened. In this way the screen is normally, as when the window is closed, completely concealed from view, and is automatically brought into use by the opening of the window. Then when the window is closed the screen is automatically rolled up again.

The object of my invention is to provide an improved construction whereby no springs will be necessary for operating the rollers, when the screens are wound up by the closing of the windows, and whereby the said rollers are operated by the usual window weights, the latter thereby serving to control the said screens as well as to counterbalance the window sashes.

The nature and advantages of my invention will, however, hereinafter more fully appear.

In the accompanying drawings Figure 1 is a front elevation of a window having an automatic screen arrangement embodying the principles of my invention, showing the sashes partly open. Fig. 2 is a vertical section on line 2—2 in Fig. 1. Fig. 3 is an enlarged detail view of a portion of one of the screens, and the adjacent portion of the sash, showing the detachable connection between the two. Fig. 4 is a view similar to Fig. 1, but showing certain portions of the frame broken away to show the arrangement of the weights and cords, and with the sashes closed. Fig. 5 is a vertical section on line 5—5 in Fig. 4.

As thus illustrated, the frame A and upper and lower sashes B and C may be of any suitable, known or approved construction. The upper sash B has a flexible screen b secured to its upper edge, which screen is carried on a roller b' concealed at the top of the frame. This roller has drums b² at the ends thereof, and the weights b³ are connected by cords b⁴ that are secured to

said drums and adapted to wind thereon and unwind therefrom. When the sash B is pulled down the screen b unwinds and the cords b⁴ are wound upon the drum b²; but when the sash is closed the weights b³ operate the roller b' to wind up the screen. The lower screen C is wound upon the roller c' at the bottom of the frame, and has its upper end secured to the lower edge of the lower sash C, whereby the screen is unwound when the sash is raised. The roller has its ends provided with drums c² for the cords c³ that have their lower ends secured thereto and their upper ends secured to the weights or counterbalances c⁴. The cords c⁵ are secured to the sash C and extend upward and over the sheaves c⁶ mounted in the sides of the frame. The other ends of these cords c⁵ are secured to the said weights c⁴. Thus the raising and lowering of the sash C serves to automatically rotate the roller c' to first unwind the screen and wind up the cords c³, and then wind up the screen and unwind said cords.

In Fig. 3 is shown an arrangement for detachably securing the reinforced edge portion c⁷ to the sash C by means of screws c⁸ adapted to extend through holes c⁹ in the screen, said holes being of a shape and size to permit the screen to be readily unbuttoned from the screw heads, whereby the sashes can be operated without the screen when such is desirable, as in winter, as for the purpose of cleaning the window.

Thus I provide an automatic window screen arrangement in which the screen rolls are operated by the same weights that counterbalance the sashes. In this way no springs are necessary for winding up the screens.

The sash cords, as shown, are wound on drums, and such drums may be of any suitable character, as, for example, those shown may be omitted and the cords wound directly upon the shafts, if such is desired, without in any way departing from the spirit of my invention.

What I claim as my invention is:—

1. A window comprising upper and lower sashes, a rolling screen for each sash, a single pair of balancing cords and weights for each sash, the weights being fixed to the depending ends of the cords thereof for each sash, the upper sash being connected with

the cords thereof through the medium of the upper screen, another pair of cords for connecting the weights of the lower sash with the lower screen, whereby the lower screen is operated positively in both directions by the lower sash, said screens being detachably connected with the sashes, and a single pair of sheaves for said window, supporting the cords and weights of the lower sash.

2. A window comprising upper and lower sashes, a rolling screen for each sash, a single pair of balancing cords and weights for each sash, the weights being fixed to the depending ends of the cords thereof for each sash, the upper sash being connected with the cords thereof through the medium of the upper screen, another pair of cords for connecting the weights of the lower sash with the lower screen, whereby the lower screen is operated positively in both directions by the lower sash, said screens being detachably connected with the sashes, a single pair of sheaves for said window, supporting the cords and weights of the lower sash, the said upper screen being secured to the inside of the upper sash, and the lower screen being secured to the outside of the lower sash, and said screens having rolls which rotate in op-

posite directions when the two sashes are 30 opened.

3. A window comprising upper and lower sashes, a rolling screen for each sash, a single pair of balancing cords and weights for each sash, the weights being fixed to the depending ends of the cords thereof for each sash, the upper sash being connected with the cords thereof through the medium of the upper screen, another pair of cords for connecting the weights of the lower sash 40 with the lower screen, whereby the lower screen is operated positively in both directions by the lower sash, said screens being detachably connected with the sashes, a single pair of sheaves for said window, supporting the cords and weights of the lower sash, said weights being all disposed in two parallel vertical planes, one at each side of the window, and said sheaves being disposed between the upper cords and the plane of 45 50 the upper sash.

Signed by me at Chicago, Cook county, Illinois, this sixth day of December, 1910.

MORTON G. BUNNELL.
